US0D1042614S

(12) **United States Design Patent** (10) **Patent No.:** **US D1,042,614 S**
(45) **Date of Patent:** **** Sep. 17, 2024**

(54) **DEVICE MOUNTING APPARATUS**

(71) Applicant: **Engineered Network Systems, LLC**,
Burnsville, MN (US)

(72) Inventor: **Terry Strand**, Owatonna, MN (US)

(73) Assignee: **Havis, Inc.**, Warminster, PA (US)

(**) Term: **15 Years**

(21) Appl. No.: **29/773,917**

(22) Filed: **Mar. 12, 2021**

(51) **LOC (14) Cl.** **18-01**

(52) **U.S. Cl.**

USPC **D18/12**; D14/452

(57) **CLAIM**

The ornamental design for a device mounting apparatus, as shown and described.

DESCRIPTION

FIG. 1 is an upper perspective view of a device mounting apparatus;

FIG. 2 is a lower perspective view of the device mounting apparatus;

FIG. 3 is a front elevational view of the device mounting apparatus;

FIG. 4 is a right side elevational view of the device mounting apparatus;

FIG. 5 is a bottom plan view of the device mounting apparatus;

FIG. 6 is a left side elevational view of the device mounting apparatus; and,

FIG. 7 is a top plan view of the device mounting apparatus. The broken line showing of environmental structure is for illustrative purposes only, and forms no part of the claimed design.

1 Claim, 7 Drawing Sheets
